DEVICE FOR PROTECTION AGAINST
POISON GASES

Louis Granger, Fils, Paris, France

Application March 11, 1937, Serial No. 130,408
In France March 16, 1936

2 Claims. (Cl. 183—4)

The present invention relates to gas masks and more particularly to a practical and advantageous construction of a receptacle adapted to contain an absorbent product, for instance, soda, to regenerate the exhaled air which may then be again aspirated together with a supply of oxygen, for protection against poison gases.

The regenerating container, according to the invention, has the following advantages: facility and security of filling and simultaneous use of all the quantity of absorbent product which is thus saturated slowly throughout and not rapidly at some points, as it does in some types of apparatus with the result of seriously impeding the circulation of air to be purified.

The essential features of a regenerating container according to the present invention reside in the provision of a particular arrangement of the passages provided for the air to be purified in the container, whereby the said air does not meet such resistance as to quickly fatigue the user of the mask, while at the same time the air is always caused to meet regeneration surfaces without following a direct and straight way between the inlet and the outlet of the container.

It is known that, in a respiratory apparatus having a closed circuit, the period of time which the user may use the apparatus depends for a given volume of the apparatus, not only upon the internal resistance offered to the circulation of the air first exhaled and then aspirated after being regenerated, but also upon more or less good regeneration. For instance, if a portion of the exhaled air passes through the apparatus without the carbonic acid contained in the air being retained in the regenerating container, the duration of the life of the apparatus is the more reduced as the amount of non-regenerated air is more important.

The devices used for obtaining the minimum resistance to the circulation of the air together with a good regeneration of this air are shown by way of example on the annexed drawing, in which:

Figure 1 is a section on the line 1—1 of Figure 2, showing a regenerating container according to the invention.

Figure 2 is a section on the line 2—2 of Figure 1.

Figure 3 is a view in perspective of a tube with grids which is introduced into the container on concluding the filling thereof.

The container 4 is provided with an inlet pipe 18 and an outlet pipe 6 for the passage of air through the apparatus intended to contain a

product absorbing carbonic acid and the moisture in the exhaled air. This product is, for instance, soda.

The container is also provided with an orifice 15a which may be closed by a threaded stopper. 5 The filling and the emptying of the absorbent material in and from the container take place through this orifice. Beneath the orifice 15a is a vertical passageway 17a which is in communication with a plurality of horizontally disposed 10 compartments 16 formed by horizontal grids 13 and vertical corrugated or undulated grids 27. The said compartments 16 contain the absorbent product. The compartment 17a is separated by partitions 13a from each corrugated passage provided between two grids 27 or between a grid 27 and a corrugated plate 27a. The width of these corrugated passages is for instance 2 mm.

The corrugations of the grids 27 and of the plates 27a should fit within each other, as shown 20 in Figure 2, so as to hinder a direct circulation of the air in a straight line. But, these corrugations should only be deep enough to produce a minimum resistance to the passage of air. Figure 2 shows such a device fulfilling both conditions and permitting the air to pass almost but not in a straight direction.

At the lower part and at the upper part of the receptacle 4 and opposite the orifices of each of the pipes 6 and 18, there are two inner inverted 30 diffusors 25 having the shape of funnels and in front of each of which is fitted a baffle 26 forming a screen.

At their upper and lower extremities, these vertical grids are soldered to solid elements of 35 the horizontal grids 13 which elements are themselves separated from each of the baffles 26 by a supplementary horizontal grid 28 which extends over the whole surface occupied in the receptacle 4 by the absorbent product in 16.

By means of the diffusor 25 and the baffle 26, the exhaled air passing through the pipe 18 are distributed over the whole surface of the upper grid 28 and then pass into the space left between the partitions constituted by the undulated and vertical grids 27, the distance separating two grids from the same partition being calculated in such manner as to correspond to the amount of air flowing between the grids. On meeting the undulations of the grids 27, this air is directed 45 on to the absorbent product whereby it loses its impurities. On reaching the lower part of the receptacle 4, the air exhaled by the user is thus totally freed from its impurities, the particles of water carried along come onto the lower baffle 50 55

26 and fall onto the free and slightly inclined extremity of the lower diffusor 25 which causes them to condense in the cavity or chamber 29 from whence they cannot pass into the pipe 6.

5 Whatever may be the position of the user of the protective device, these particles of water are always retained in one of the two chambers 29 which are closed so as to prevent these particles of water both from getting into one or the other 10 of the pipes 6 or 18 or of returning into the part of the receptacle 4 containing the absorbent product 16.

15 The various elements of the grids or metal horizontal fabrics 13 may be mounted as shown by Fig. 2 of the drawing, that is to say, they may be distributed according to baffles between the vertical and undulated grids 27.

20 From the foregoing it will be apparent that the present invention provides a receptacle for use in connection with gas masks wherein the absorbent material is removable by tilting the container toward the passage 17a and then discharging it through the opening 15a. To renew the absorbent material it is only necessary to place 25 a sufficient quantity in the passage 17 and then tilt the receptacle in the opposite direction to that in which it is emptied and thus pack the material in the compartments 16. This operation may be repeated until the compartments are 30 filled. Since the spaces between the sinuous walls 27 and 27-27a are blocked by the walls 13a at the passage 17, these spaces will be kept clear for 35 the passage of air. After the compartments have been filled, the perforate unit 17 containing absorbent material may be inserted in the vertical passage 17a.

I claim:

40 1. In a container for absorbent material intended to regenerate exhaled air in a respirating apparatus for protection against poison gases, a container body having upper and lower gas orifices and a filling opening, means forming a passage parallel to a side wall of the container and below said filling opening, spaced horizontal 45 grids each having one end abutting one side of the casing and their opposite end terminating in

a plane defining one wall of said passage, vertically spaced grids cooperating with said horizontal grids to provide compartments opening at one end into said passage, said vertical grids being corrugated and arranged to provide sinuous 5 air passages communicating with the upper and lower gas orifices and the depth of the corrugations being such as to present a minimum resistance to air flow while causing the air to meet successively the corrugations of the vertical grids 10 in which the absorbent material is packed, and means at the ends of said vertical grids located adjacent said passage to prevent absorbent material from entering the spaces between the corrugated vertical grids. 15

2. A regeneration unit for use in poison gas masks, comprising a casing having a filling opening at one corner provided with a removable cap, inlet and outlet connections for the casing, a plurality of absorbent containers in the casing 20 and arranged to abut one of the inner side walls thereof and spaced from the other inner side wall to provide a vertical passage below the filling opening, said absorbent containers each including a pair of corrugated perforate partitions disposed vertically in the casing and the adjacent walls of adjacent containers being spaced apart to provide a sinuous air circulating passage, a plurality of horizontal foraminous grids arranged in vertically spaced relation between each pair 25 of said partitions and forming cells communicating at one end with said vertical passage to receive absorbent material inserted through the filling opening, corrugated plates arranged between the outer perforate partitions of the containers and the casing to provide additional sinuous air passages, and wall members located in said vertical passage and fitted to the ends of the corrugated perforate partitions and also between said corrugated perforate partitions and 30 said plates to prevent absorbent material from entering the said sinuous air passages formed by the corrugated partitions and plates thereby to maintain said sinuous passages clear for the passage of air. 35
